HEAT CONTROLLING AND REGULATING DEVICE

Arthur Cahn, New York, N. Y., assignor to
John J. Cahn, New York, N. Y.

Application October 19, 1940, Serial No. 361,985

7 Claims. (Cl. 200—37)

This invention relates to a controlling or regulating device adapted for various uses wherein closing of one or more electric circuits for predetermined periods of time is desirable, and particularly adapted for use in connection with heating plants. It is especially adapted for use in cases where the operation of an oil burner, electrically operated stoker, hot water supply means or other electrically-controlled mechanism is operated according to prevailing temperature either indoors or outdoors.

The primary object of the invention is to provide a relatively simple and efficient device which will be reliable and accurate in operation under all working conditions, whereby a maximum of heating efficiency will be obtained for minimum fuel consumption.

Another object of the invention is to provide means by which several electrical circuits, such as one controlling the operation of a heating plant and another for controlling hot water heating may be effectively operated by means of a single rotating element.

Another object of the invention is to provide a device of this character of great flexibility and capable of either complete thermostatic control or manual control, or partly thermo-responsive and partly manual control.

In the accompanying drawings wherein an embodiment of the invention is shown, Fig. 1 is a front view of a device made in accordance with the invention; Fig. 2 is a sectional view on the line 2—2 of Fig. 1, looking in the direction of the arrows; Fig. 3 is a sectional view on the line 3—3 of Fig. 1, looking in the direction of the arrows; Fig. 4 is a face view of the control drum arranged flatwise to disclose the calibrations and the manner in which the contact plates may be fitted in the drum; Fig. 5 is a vertical sectional view through the drum and mounting therefor; Fig. 6 is a view of one side of one of the contact plates; Fig. 7 is a view of the opposite side of the contact plate; Fig. 8 is an end view of the same contact plate; Fig. 9 is a perspective view of one of the contact plates used in the part of the device for controlling hot water heating; Fig. 10 is a front view with parts in section, of the means for the pivotally moving contact finger; and Fig. 11 is the wiring diagram for the device.

With reference to Fig. 1, 1 indicates an electric motor of the synchronous type, the construction of which is conventional and need not be described in detail. It is sufficient to say that the same is secured at one side of the frame of the device and it drives suitable gearing indicated

generally at 2. A shaft 3 is mounted to rotate between upstanding plates 4 and 5 forming sides of the supporting frame of the machine. Said plates 4 and 5 have their lower ends formed with feet 6 (Fig. 2) secured upon a flat base member 7 and the plates are held in spaced relationship at their upper ends by means of the transversely-extending brace rod 8. The operation of the synchronous motor 1 is such that it rotates the shaft 3 one revolution in each twenty-four hours.

Secured upon the shaft 3 by means of a set screw 9 (Fig. 5) is a ratchet wheel 10 formed with a hub 11 through which the set screw 9 extends to secure the ratchet wheel to the shaft 3. Since ratchet wheel 10 is secured to shaft 3 it is therefore rotatable with the shaft and makes a complete revolution in each period of twenty-four hours. Mounted free on the shaft 3 is a drum 12 made of insulating material such as "Bakelite," hard rubber, or any other suitable insulation. The drum is of hollow conformation and has the central web 13 and integrally formed circumferential rim 14. Secured to one face of the web 13 is a suitable friction material 18, such as leather or the like, and this is held in frictional engagement with a face of the ratchet wheel 10 by means of a coil spring 15 surrounding the shaft 3 and urged against the web 13 of the drum by means of a collar 16 secured on the shaft 3 by set screw 17. The pressure of the spring 15 is such that it forces the facing material 18 into frictional engagement with the face of the ratchet wheel 10 so that as the ratchet wheel is rotated, it serves to rotate the drum 12 with it.

The web 13 of the drum also carries a pawl 19, pivoted on pin 20, and urged against the teeth of the ratchet wheel 10 by means of the spring 21. The pawl and ratchet engagement just described aids in driving the drum from the ratchet wheel 10, and it also permits manual rotative movement of the drum on the shaft 3 for adjustment purposes whenever desired. The drum 12 is rotated clockwise by the motor, as viewed in Fig. 2 and adjustment of the drum by hand may be had at any time by rotating the drum in the same direction, the pawl and ratchet permitting such movement, but opposing movement in the opposite direction.

The periphery of the drum 12 is calibrated into twenty-four divisions (Fig. 4) as indicated by the numerals 1 to 12 repeated, each of these divisions representing the distance that the drum will be rotated in the period of one hour. The shaded calibrations indicated at 22 represent the

night hours, while the unshaded calibrations, indicated at 23, represent the hours during the day. Extending inwardly from one of the edges of the rim of the drum is a plurality of equally spaced slots 24, said slots being so spaced from one another that the space between them represents the distance that the drum will rotatively travel during a period of one-half hour. Each of these slots 24, or as many of them as may be required, is intended to receive and hold a contact plate such as indicated at 25, and shown in detail in Figs. 6 to 8 inclusive.

Each contact plate consists of a cylindrical, resilient portion 26 from which extends the integral, springy jaws 27 tending to normally spring or spread apart to a limited extent. One of said jaws is provided with an integrally formed, laterally bent plate portion 28 of tapered formation, which when the contact plate is inserted in one of the slots 24, overlies a portion of the outer surface or periphery of the rim 14 of the drum 12 and conforms smoothly to the shape thereof, so that a wiping contact finger 29, to be later described, will slide easily over the face portions 28 of as many of the contact plates as may be exposed on the surface of the rim of the drum.

Each of the contact plates 25 is removable from the slot 24 in which it is placed, said contact plates each retaining its position in the slot by the resilience of the jaws 27 and because of their tendency to spread apart within the confines of the slot. The contact plates 25 being thus solely retained within the slots by their resilience, may be readily manually removed when desired or shifted about from one slot to another as required to suit individual operating conditions.

The face portion 28 of each of the contact plates 25 is tapered or gradually reduced in width as shown in Figs. 1, 4 and 6, said face portion having a wider end 29a disposed at the open or entrance end of the slot 24 in which the contact plate is inserted, and its narrower end 30 disposed adjacent to and extending slightly beyond the inner or closed end of the slot. The wider portion 29a of the face 28 is of such width that it extends from the slot in which the contact plate is located to the next slot, so that when a number of the contact plates are placed in adjacent slots 24, a continuous contact surface will be provided on the periphery of the drum adjacent to the right hand edge thereof, or in other words, adjacent to the open ends of the slots 24. The narrower end 30 of the contact face 28 is of such width that it represents the distance that the drum will rotate in a period of approximately ten minutes, although this period may be varied for any other division of time, dependent upon the width of the contact surface formed on the contact member. Accordingly, when the drum is rotated and the contact finger rides over any desired width of the contact surface 28, a circuit to a heating device, such as an oil burner, electrically-operated stoker or the like will remain closed and the heating device will be operated for the period that the finger is in wiping contact with the portion of the face 28 movable beneath it.

The contact finger 29 is secured, adjacent to its lower end, by the screws 31, to a yoke 32 of insulating material, said yoke being pivotally mounted on the pivot pin 33, supported in the upstanding flanges 34 and 35 of a bracket 36 secured on the top of the base 1. A torsional

spring 37 surrounds the pin 33 and has one end engaging against the bottom of the bracket 36 and the other end engaging against the yoke 32 and tending to swing the yoke and finger 29 secured to it toward the left as viewed in Fig. 1, and tending also to hold the pin 38 extending between and connecting the legs of the yoke 32 into contact with a collar 39 secured by pin 40 on a longitudinally movable rod 41, adapted to slide lengthwise in brackets 42 and 43 rising from the bracket 36. The rod 41 is surrounded by a coil spring 44 which has one end bearing against the bracket 42 and the other end bearing against a cup-shaped head 45 fixed on one end of the rod 41.

At 46 is a thermostatic bellows of conventional form supported in an adjustable bracket 47. One end of said bellows is held in contact with the head 45 by pressure of the spring 44. Connected to the bellows 46 is a flexible tube 48 having its opposite end attached to the cylinder 49. Said cylinder 49, the tube 48 and bellows 46 contain a thermo-responsive fluid or gas which tends to expand or cause retraction of the bellows 46 according to temperature operative upon the cylinder 49, which is generally exposed externally of the building to be heated, or at any point of location, the temperature of which is to control the operation of the heating plant.

The bracket 47 carrying the thermo-bellows 46 is adjustable longitudinally in the bracket 36, said bracket 47 having a foot portion 50 guided between the flanges 31 and adjustable in the bracket 36 by means of a shaft 52 having the threaded end portion 53 operative through a threaded opening in bracket 47.

The shaft 52 is rotatably mounted in the brackets 42 and 43 and is restrained from longitudinal shifting movement therein in one direction by means of a collar 54 secured on the shaft and in the opposite direction by means of the bevel gear 55 attached at the end of said shaft. The bevel gear 55 meshes with another bevel gear 56 secured on a transverse shaft 57 rotatable in upstanding lugs 58 and 59 rising from the base of the bracket 36. The transverse shaft 57 carries a knob 60 by which the shaft 57 is rotated when desired to manually cause the contact finger 29 to be shifted to either the left or right to secure a greater or lesser heat range. A calibrated dial plate 60a aids in finding suitable position of adjustment for the knob 60.

It will be obvious that when the knob 60 is turned to the right, as viewed in Fig. 1, shaft 52 will be so rotated that the bracket 47 will be shifted to the right, thus bodily moving the bellows 46 in the same direction. As the bellows is thus shifted over toward the right, spring 44 causes the rod 41 to follow it. The rod 41, on such longitudinal shifting movement, brings the collar 39 into contact with the cross pin 38 which swings the yoke 32, carrying the finger 29, to the right. A stop pin 61, extending through the rod 41 limits the movement of said rod to the right. In normal operation, when the temperature effective upon the cylinder 49, is relatively high, the bellows 46 is expanded and the pressure of the bellows, imposed upon the head 45 forces rod 41 toward the left, so that the collar 39 is moved with the rod. The torsional spring 37 swings the yoke 32 toward the left, normally maintaining the transverse pin 38 against the collar 39. Since it is only necessary that the upper end of the contact finger swing slightly beyond the narrower end 30 of each of the con-

tact members 25 in order to open the circuit controlled by co-operation of the finger with the contacts 25, further swinging movement of the finger toward the left is unnecessary and is accordingly prevented by the stop 62 adjustable in the bracket 43. Should the bellows 46 be expanded to an extent greater than is required to move the contact finger 29 to the limit of its required swing, the rod 41 may continue its movement under the pressure of the expanded bellows without affecting the yoke 32 since the collar 39 will simply be shifted to the left, leaving the yoke 32 resting against the stop 62 and held thereagainst by the pressure of the torsional spring 37. Moving the knob 60 to the left will cause the bracket 47 to be shifted to the left so that its action to swing the finger 29 to the left will be effective sooner or at a lower temperature, so that a lesser heating period will be obtained.

Extending inwardly from the opposite edge of the rim of the drum is a plurality of spaced slots 75, said slots being positioned similarly to those indicated at 24 but located at the opposite edge of the rim of the drum. That is to say, each slot 75 is located at one of the half-hour marks so that the distance between each two slots is that traversed by the drum during a half hour period. Each of the slots 75, or as many of the slots as desired, is adapted to receive a contact plate 76 shown in detail in Fig. 9. These contact plates are similar in construction to those indicated at 25 except that the face portion 77 thereof is of uniform width and when one of the contact members is inserted in one of the slots 75, its face portion 77 extends to the next slot and abuts against the end of the similar contact plate located therein. Accordingly, when a number of adjacent contact plates 76 are inserted in the slots, a continuous contact surface will be provided along that edge of the drum where the contact members 76 are located. This will be seen in Fig. 4 in the area between 5:30 in the night hours and 10:00 o'clock in the night hours also, the continuous contact surface thus being shown as extending through all of the daylight period and through a portion of the early morning and evening until 10:00 P. M. The purpose of this arrangement will be presently explained. It will be noted in Fig. 4 that the width of the contact surface 77 on each of the contact plates 76 is less than the depth of each of the slots 75 so that the contact plates 76 may be positioned in the slots either toward the inner ends of the slots as shown at the upper and lower portions of Fig. 4, or else may be positioned toward the outer or open ends of the slots as shown in the slots beginning at 5:30 a. m. and ending at 10:00 p. m. The latter position of the contact plates is the operative or circuit-closing position, for when a contact plate is in said position and the drum is rotated, the contact plate is located to bridge a pair of stationary resilient fingers 78 and 79 secured in spaced relationship by screws 80 to a block of insulating material 81 fastened to an arm 82 (Fig. 3) formed on and projecting from the frame plate 4. These spaced resilient fingers 78 and 79 constitute wiping contacts which bear against the periphery of the drum and wipe against the contact plates 76 as the drum is rotated. When the contact plates 76 are disposed inwardly toward the inner ends of the slots, the contact plates will touch only one of the fingers, namely finger 78 and will therefore not bridge the fingers or close the circuit.

to be later described, for operating a hot water heating means or other device.

The insulating block 81 also carries a fixed bent finger 83 which constitutes a time-telling hand, the same indicating the time given by the calibrated portion of the drum, and also constituting a means by which the device may be set when required.

The frame plate 5 is provided with a forwardly extending integral arm 84 to which is secured an insulating block 85 to which is fastened by screws 87 a contact finger 86 which operates against the periphery of the drum adjacent to the edge of the same wherein the contact members 25 are positioned, the end of said finger bearing against the wider portions 29a of the contact faces 28 when the drum is rotated.

To fully comprehend the operation of the device as employed for the purpose of controlling a heating plant and water heating means, the electrical circuit disclosed in Fig. 11, must be understood. Therein, the two wires indicated at 90 and 91 constitute the wires carrying conventional lighting circuit current. A wire 92 extends from wire 91 to the synchronous motor 1. Wire 93 connected into wire 90 also connects to the synchronous motor, a manually operated switch 94 being interposed in the wire 93. Connected to wire 93, at a point between the switch 94 and the motor 1 are wires 95 and 96, that shown at 95 being connected to the fixed contact finger 78, while that shown at 96 is connected to the movable contact finger 29. One end of the winding of a relay 97 is connected to power line wire 91, the other end of the relay coil being connected to the contact finger 79. When the relay 97 is energized by closure of the switch 94 and by bridging of the contact fingers 78 and 79 by one of the contact members 76, it closes circuit between wires 98 and 99 one of which connects with wire 100 and the other to wire 100a. Wires 100 and 100a together constitute a lead from an electrically operated water heating device which will, by closure of circuit between wires 100 and 100a by relay energization be caused to operate and will continue to do so as long as the manually operated switch 94 remains closed and the contact fingers 78 and 79 are bridged by one or the other of the contact members 76.

The fixed contact finger 86 is electrically connected to one end of the winding of a relay 101, the other end of the winding being connected by wire 102 to the power line wire 91. From this arrangement it will be clear that when switch 94 is closed and the pivoted finger 29 and fixed contact finger 86 are bridged by one of the contact members 25 the relay coil or winding 101 will be energized and it will close circuit between wires 104 and 105. Wire 104 is connected to wire 107a, while wire 105 is connected to wire 107, the wires 107 and 107a constituting a lead from the circuit of the oil burner, electric stoker or the like. A manually-operated switch 106 is interposed in the wire 105 while a similar manually-operated switch 103 is interposed in the wire 98. In the normal operation of the device, these switches remain in open condition and are for use only when it is desired to disconnect the control mechanism for either the heating plant, the water heating means or both, and thereby permit the heating devices to function without the use of the timing means.

In Fig. 4, the contacts carried by the drum 12 are arranged for the normal heating and hot

water supply control for an average building. At the top of the figure, beginning with 12:30 at night, and extending down to 4:30 a. m. a number of relatively narrow contacts 25a are mounted in the slots 24 of the drum. Since little or no heat is needed during these night hours, unless very low outside temperature prevails, the movable contact finger 29 will be generally disposed to the left and situated beyond the inner ends of the contacts 25a so that circuit between the movable contact finger 29 and fixed contact finger 88 will remain open during this period. Beginning at 4:30 a. m. the contacts gradually taper or as indicated at 25b, 25c, and 25d, so that one of these contact plates will come beneath the contact finger 29 and circuit will be closed between contact fingers 29 and 88, thus energizing the relay coil 101 which will at once close circuit between wires 104 and 105 holding it closed and starting the burner in operation. Manually operated switches 103 and 106 are kept in open position and should remain so as long as the control apparatus is electrically maintained in circuit with the heating plant. As the rotation of the drum 12 continues, the contact members 25e are next brought beneath the contact finger 29 and since these contact members 25e are full width, they together constitute an hour's operating time for the burner. With this arrangement, the hour's operation will occur between 6 and 7 a. m. and this constitutes a morning "pick-up" for the heating plant, such period of time being usually sufficient to initially heat up the building. Thereafter, the tapered contact members 25 occur in sequence until 10:00 p. m. when the narrower contacts 25a again appear.

With the arrangement of contacts disclosed, and which is merely a suggested arrangement found adaptable for some heating purposes, and particularly for apartment buildings and the like, it will be seen that a definite, well-planned heating schedule results. Beginning in the early morning, the heating plant will start with a selected continuous heating period, as for example, the one hour period attained by the use of the two contacts 25e. Thereafter, the tapered contact members 25 will produce interrupted operating periods according to the position of the movable contact finger 29 in relation to the tapered contact surfaces 28, the position of said finger being determined by thermostatic control exerted by elements 46, 48 and 49 as previously explained. At 10:00 p. m. or at such other selected night hour the narrower contacts 25a again are brought adjacent the contact finger 29, and unless unusual cold weather is existent, the contact finger 29 will be located to the left of these contacts 25a and the burner will not operate during the night hours. If however, real cold weather is prevailing, the finger 29 will be disposed sufficiently to the right to rest upon contacts 25a and the burner will operate until the temperature rises sufficiently to shift it to the left and off the contact plates 25a.

As heretofore stated, the arrangement of contacts disclosed is purely illustrative for since the contact plates are removable and interchangeable, they may be shifted about to suit specific requirements for individual heating plants.

The contact plates 76 disposed in the slots 75 at the opposite edge of the drum are primarily used for the control of a water-heating device. During the night, early morning and evening

hours, the contact plates may be shifted to the inner ends of the slots 75 representing such hours, so that the heating of the water will be discontinued during that period. During the daytime, the contact plates in slots representing daylight and evening hours may be disposed toward the outer or open ends of the slots so that they bridge the contact fingers 78 and 79 as the drum is rotated and by energizing the relay coil 97 circuit between wires 98 and 99 will be closed and the water heater maintained in operation. The contact members 78 may be placed in such slots as is desired and may be omitted from other slots so that interrupted operation of the water heater will be had to provide sufficient hot water at a minimum of heating expense.

Should it be desired to operate the device with only the room-heating control in use, it is merely necessary to manually close the switch 103. This closes circuit between wires 100 and 100a and subsequent operation of relay 97 has no effect on the water-heating circuit of which wires 100 and 100a form a part. Also, if it should be desired to render the heating control inoperative, switch 106 is manually closed. This closes circuit between wires 107 and 107a and renders subsequent operation of the relay 101 ineffective on the oil burner or electric stoker circuit. Of course, the entire control device may be rendered inoperative by opening switch 94 and closing switches 103 and 106. When this is done, the entire device is completely out of the heating and hot water circuits.

While I have shown and described one embodiment of the invention, it is obvious that the same is not to be restricted thereto since many modifications may be made without departing from the spirit of the invention. For example, while I have shown a temperature-controlled means for shifting the position of the contact finger 29, such means consisting of elements 46, 48 and 49 may be readily detached and the finger 29 may be shifted manually to any selected position across the length of the contact members. The arrangement of the contact members; the positions of the slots in which the same are located, the calibrations appearing on the drum, the shape and disposition of the drum; the manner in which it is mounted on, adjusted and driven by the shaft from the synchronous motor, are all elements capable of alteration and modification to suit various requirements. I therefore do not limit the invention to the specific disclosure but consider the same as comprehending all structures coming within the scope of the annexed claims.

What I claim is:

1. In a device of the character described, a rotating drum and means for rotating the same at a predetermined speed, said drum having a circumferential rim, the rim having a plurality of spaced slots extending inwardly from one of its edges, any of said slots being adapted to receive a metal contact member, said contact member having a face portion resting flatwise against and conforming to the surface curvature of the outer face of the rim, said face portion of each contact member being tapered in width with its widest part situated adjacent to the edge of the drum, said contact member being provided with spaced jaws extending into the slot and resiliently operative against the sides of the slot to retain the contact member in position, a contact finger bearing against the periph-

ery of the drum and riding over the face portions of the contact members disposed thereon.

2. In a device of the character described, a rotating drum and means for rotating the same at a predetermined speed, said drum having a group of spaced slots extending inwardly from each of its opposite edges, each group of slots adapted to removably receive metal contacts, a contact finger riding against the face of the drum and over the contacts in one group of slots, a pair of spaced contact fingers riding against the drum adjacent the contacts in the second group, the latter contacts being adapted to bridge the spaced contact fingers and close an electric circuit between the same upon rotation of the drum.

3. In a device of the character described, a drum rotated at a predetermined speed, the drum being provided with a plurality of spaced slots opening at one edge of the drum and extending inwardly from the edge of the drum, spring contact plates fitted in said slots and having face portions overlying parts of the periphery of the drum, said face portions tapering from the edge of the drum to the inner ends of the slots, and a contact finger urged against the periphery of the drum and into contact with the face portions of the plates when the drum is rotated.

4. In a device of the character described, a rotated drum bearing horological calibrations, means for rotating said drum at a predetermined speed, spaced slots in the periphery of the drum, a contact plate resiliently held in each slot, each contact plate having a bent face portion overlying the face of the drum, said face portion being tapered and having a part extending from one slot to the next, and a pair of wiping contacts bearing against the drum and riding over the contact plates, one of said contacts being adjustable relative to the plate.

5. In a device of the character described, a drum having a plurality of spaced contacts arranged along one of its edges, the drum having slots in which said contacts are held, said contacts being adapted to be positioned either near the inner closed ends of the slots or adjacent to the open outer ends thereof, and a pair of spaced fingers against which the contacts wipe and bridge when the contacts are in one of the two positions in the slots.

6. In a device of the character described, a rotating member having a plurality of spaced slots extending inwardly from one of its edges, a contact adapted to fit into any one of said slots, said contact having a substantially flat face portion extending over and conforming to a portion of the face of the rotating member, said contact being provided with spring-actuated jaws adapted to engage the walls of the slot in which it is placed to permit lateral adjustment of the contact in the slot and prevent unintentional displacement of the same out of said slot.

7. In a device of the character described, a rotating member having a plurality of spaced slots extending inwardly from one of its edges, a contact adapted to fit into any one of said slots, the contact having a substantially flat face portion extending over and conforming to a portion of the face of the rotating member, said contact being provided with a pair of hinge-ably connected jaws adapted to resiliently engage the walls of the slot in which the contact is placed, the hinge portion for said jaws being enlarged to a size greater than the width of the slot, whereby the body of the rotating member is disposed between the flat face portion and the enlarged hinge portion and the contact is prevented from displacement out of the slot.

ARTHUR CAHN.
